CLAIM

(22) Filed: Aug. 31, 2004

The ornamental design for beauty appliances washer using ultrasonic waves, as shown and described.

(30) Foreign Application Priority Data

DESCRIPTION

Mar. 19, 2004 (KR) 30-2004-0007938

FIG. 1 is a perspective view of beauty appliances washer using ultrasonic waves according to my new design;

(51) LOC (8) Cl. 15-05

FIG. 2 is a front view of beauty appliances washer using ultrasonic waves according to my new design;

(52) U.S. Cl. D32/1; D28/44

FIG. 3 is a rear view of beauty appliances washer using ultrasonic waves according to my new design;

(58) Field of Search D32/1, 25; 15/1,

15/104, 92, 310; 134/92, 135, 201, 107;

320/115; 30/34.05, 541, 537-538, FOR 105;

206/351; D6/526; D28/44, 73; D13/108

15/104, 92, 310; 134/92, 135, 201, 107;

320/115; 30/34.05, 541, 537-538, FOR 105;

206/351; D6/526; D28/44, 73; D13/108

(56) References Cited

FIG. 4 is a left side view of beauty appliances washer using ultrasonic waves according to my new design;

FIG. 5 is a right side view of beauty appliances washer using ultrasonic waves according to my new design;

FIG. 6 is a plan view of beauty appliances washer using ultrasonic waves according to my new design; and,

FIG. 7 is a bottom view of beauty appliances washer using ultrasonic waves according to my new design.

15/104, 92, 310; 134/92, 135, 201, 107;

320/115; 30/34.05, 541, 537-538, FOR 105;

206/351; D6/526; D28/44, 73; D13/108
